UNITED STATES PATENT OFFICE

JOSEPH HAZELDINE, OF ZION, ILLINOIS, ASSIGNOR TO RICHMOND LACE WORKS, INC.,
OF ALTON, RHODE ISLAND, A CORPORATION OF MASSACHUSETTS

DESIGN FOR LACE OR ARTICLE OF ANALOGOUS NATURE

Application filed September 2, 1932. Serial No. 44,747. Term of patent 7 years.

To all whom it may concern:

Be it known that I, JOSEPH HAZELDINE, a citizen of the United States, residing at Zion, in the county of Lake and State of Illinois, have invented a new, original, and ornamental Design for Lace or Article of Analogous Nature, of which the following is a specification, reference being had to the accompanying drawing, forming part thereof.

In the accompanying drawing the figure is a view, in plan, of a portion of a piece of lace showing my new design, it being understood from the illustration that the design is repeated throughout the piece.

I claim:

The ornamental design for lace or article of analogous nature, substantially as shown.

JOSEPH HAZELDINE.
